PRECISION TIMER

Edward Timbs, Los Angeles, Calif., assignor to
 The National Supply Company, Pittsburgh, Pa.,
 a corporation of Pennsylvania

Application June 23, 1944, Serial No. 541,834

7 Claims. (Cl. 161—7)

This invention relates to precision timers and more particularly to a timing device adapted to control the flow of a fluid under pressure.

It is an object of this invention to provide a timing device which is precision controlled to determine accurately the intervals of opening and closing of a valve controlling the flow of a fluid under pressure.

Another object of this invention is to provide a precision timer for actuating a valve in a fluid pressure supply system which is adapted to be driven by a precision instrument such as a clock mechanism, or synchronous electrical motor.

Another object of this invention is to provide a precision timing mechanism which includes a rocking beam carrying a movable weight, which rocking beam is pivoted to rotate in accordance with the load as determined by the moving weight and wherein means are provided for actuating the rocking beam which permits of the independent control of the periods of time of opening and closing of the valve actuated by the rocking beam.

Another object of this invention is to provide a precision timer which includes a mechanism which may be powered by spring wound clock or small synchronous electric motor with no change to the timer except the change of power units.

Other objects and advantages of this invention it is believed will be apparent from the following detailed description of a preferred embodiment thereof as illustrated in the accompanying drawings.

In the drawings:

Figure 1 is an elevation of the precision timer embodying my invention.

Figure 2 is an end elevation thereof with the enclosing case broken away to illustrate the operating mechanism.

Figure 3 is a sectional view taken substantially on the line 3—3 of Figure 2.

Figure 4 is a sectional plan view taken substantially on the line 4—4 of Figure 1.

Figure 5 is a diagrammatic view illustrating an adaptation of the precision timer embodying my invention.

Figure 6 is a diagrammatic view of a modified form of timer mechanism embodying my invention.

Figure 7 is an end view thereof.

In the preferred embodiment of my invention illustrated in the accompanying drawings, I have shown in Figure 5 the adaptation of the precision timer in a fluid pressure supply system wherein the timer diagrammatically illustrated at 1 is utilized for controlling the intervals of time dur-

ing which gas under pressure flows through a pipe 2 to provide gas under pressure for raising a fluid such as oil in a well. The timer 1 is supported upon a leg 2' which is suitably held by means of a bracket 3 upon the pipe structure.

Mounted in the pipe 2 is an inlet valve 4 by which the flow of gas into the pipe 2 may be manually controlled. A similar discharge control valve 5 is provided in the pipe 2. A valve 6 controls flow of gas through the pipe 2 in accordance with the pressure of the gas. The operation of the motor valve 6 from closed to open position is controlled by means of a pressure diaphragm 7 so that when there is a sufficient pressure of gas upon the upper surface of the diaphragm 7, the valve 6 is moved to an open position to permit direct flow of gas under pressure through the pipe 2 and out through the discharge valve 5. The operation of the diaphragm 7 is preferably controlled by low pressure gas from any suitable or desirable source and this low pressure gas is admitted to the upper surface of the diaphragm 7 through a conduit 8 from a supply conduit 9. As viewed in Figure 3, the supply conduit 9 and the conduit 8 leading to the diaphragm 7 are connected into a valve block 10. The valve block 10 has formed therein a valve chamber 11 in which a valve block 12 is mounted. The conduit 8 is in communication with the chamber 11 through a duct 13 while the supply conduit 9 communicates with the chamber 11 through an inlet duct 14 formed in the block 10.

The valve 12 has a conical head 15 adapted to seat on a correspondingly formed seat 16 formed in the control passage 17 which connects the inlet duct 14 with the chamber 11. The valve 12 is connected by means of a valve stem 18 with an upper plug 19 which is mounted to reciprocate in the vertical branch 20 of the valve block 10. The valve block 10 is mounted in a frame 21 supported upon the base 22 of the timer. The frame 22 is provided at its upper end with a horizontal plate 23 having an aperture therein through which the valve block branch 20 extends.

Securing nuts 24 and 25 are threaded to the branch 20 on opposite faces of the plate 23. Formed upon the plate 23 to one side of the nuts 24 and 25 is a U-shaped bracket 26 within which there is carried upon the bracket pin 27 a valve actuating rod 28. The valve actuating rod 28 engages the upper end of the plug 19, the upper end of the plug 19 being extended beyond the branch 20.

As the point of engagement of the valve lever 28 is relatively close to the center of the pin 27,

the extension of the rod 28 is of mechanical advantage over the upward thrust of the plug 19 tending to hold the valve block 20 in closed position under the influence of the spring 29 mounted in the valve chamber 11. The lower end of the chamber 11 is closed by means of a closure cap 30.

At the outer end of the lever 28 is carried an adjustable stop or engaging screw 31 which is threaded into the end of the lever 28 and is locked in adjusted position by means of a lock nut 32.

A rocker 33 is fulcrumed on pins 34 carried by the frame 21. This rocker 33 is formed to provide a channel 35 in which a weighted ball 36 is adapted to travel. The rocker 33 has end plates 37 between which there is mounted a retention rod 38 adapted to engage the ball 36 and retain the ball in rolling position within the channel 35.

The rocker 33 is provided with a pressure foot 39 adapted to engage the upper end of the screw 31 to depress the lever 28 under the weight of the ball 36 and hence move the valve plug 19 downward to depress the valve 12 in the valve chamber 11 and permit gas to flow through the spiral groove 40 of the plug from the inlet pipe 9 to the conduit 8 leading to the diaphragm 7. Means are provided for rocking the rocker 33, which means provide for the precision opening and closing of the valve 12 so that gas may flow to the diaphragm 7 for the opening and closing of the valve 6 in accordance with the desired timing of the flow of gas or other fluid under pressure through the conduit 2. This means is preferably of the following construction:

Mounted in the frame 21 is a shaft 41 which is journaled upon bearings 42. Secured to the opposed ends of the shaft 41 beyond the frame 21 are timing discs 43 and 44. Each of the timing discs 43 and 44 has a plurality of edge perforations 45 adapted to receive securing screws 46 for affixing of the cam surface members 47 in selected positions around the periphery of the disc. These cam members present inclined cam faces 48 which project beyond the edge of the discs 43 and 44, pass under and engage cam rollers 49 and 50 carried respectively at the opposed ends of the rocker 33. The cam rollers are carried on the lower surface of the rocker 33 on pins 51 mounted in brackets 52.

By varying the positions of the cam members 47 on the periphery of the two timing discs 43 and 44 and as said discs are driven in rotation, it will be apparent that the rocker 33 is alternately tipped to and from the position illustrated in Figure 2 on its carrying trunnion 34 with the result that the ball 36 rolls back and forth through the channel 35 to engage the respective ends 37 of the rocker 33. When the ball 36 occupies the position shown in Figure 2, the rocker is disengaged from the valve actuating lever 28 permitting the spring 29 to move the valve plug 12 to closed position shutting off the gas flow. When the ball 36 is rolled to the opposite end of the rocker 33 its weight causes the lever 28 to be depressed with the result that the plug 19 within the branch 20 moves downwardly therein, moving the valve 12 to open position. Thus an exact timing of the opening and closing of the valve may be had, depending only upon the timing or speed of rotation of the shaft 41. Any suitable or desirable means may be provided for rotating the shaft 41, which means as herein illustrated may include a pinion 53 which is secured to the shaft 41.

The gear 53 is adapted to mesh with an idler

pinion 54 carried upon a lever arm 55. The lever arm 55 has its hub portion 56 journaled on the shaft 41. The idler pinion 54 in turn meshes with a drive gear 57. The drive gear 57 may in turn be driven by any suitable constant speed mechanism.

As illustrated in Figures 1 and 2, this constant speed driving mechanism constitutes a clock mechanism of the spring powered type mounted within a case 58 supported upon the base 22. In this case the drive gear 57 is driven by the minute hand shaft of the clock mechanism and is therefore driven at a definite speed as determined by the clock mechanism. The utilization of the clock as a driving means is particularly advantageous in places where other sources of power are not available or convenient and by employing for example an eight-day clock mechanism for driving the gear 57, it is apparent that the spring driving the clock mechanism will only have to be periodically wound in order to carry out functions of the precision timing means.

In Figure 4 I have illustrated a modification wherein the drive gear 57 is driven through the medium of a reduction gear 59, the enclosing case of which is mounted on the base 22 in the position of the clock case 58. This reduction gearing may be suitably driven by a synchronous electric motor diagrammatically illustrated in Figure 4 at 60. In this case the synchronous electric motor drives the driven shaft 61 of the reduction gearing while the driving gear 57 is secured to driven shaft 62 of the reduction gearing. Any suitable or desirable form of reduction gearing may be employed so that it is deemed unnecessary to describe in full the reduction gearing illustrated.

In Figures 6 and 7 I have indicated a further modified form of my invention wherein the timing means of my invention is utilized for the controlled timing actuation of a solenoid valve. In this modification I have not shown the details of the valve but have illustrated the adaptation of the timing means of my invention for controlling the actuation of a switch positioned in the electric circuit leading to the solenoid (not shown) utilized for actuation of the valve.

In this modification of my invention the rocker 33^a is adapted to be actuated by a pair of timing discs 43^a and 44^a substantially as described and illustrated in connection with the modification of Figures 1 to 5, inclusive. The discs 43^a and 44^a may be driven by any suitable timing means such as a small synchronous electric motor or a spring-wound clock, which power means are interchangeably used as described in connection with the previously described modification. The rocker 33^a of this modification is pivotally supported on a pivot 34^a. At the end of the lever 28^a there is positioned an actuating pin 32^a supported in position to engage the actuating button 39^a of a mercoind switch 60^a. This mercoind switch is connected within the electric circuit indicated by the wires 61^a leading to the solenoid (not shown) for actuating a control valve which may be mounted in the low pressure lines 8 and 9 for supplying pressure to the diaphragm 7 for actuation of the control valve 6.

The lever 28^a is supported by the opposed frame plates 21^a. Also supported by the frame plates 21^a is a stop pin 62^a positioned upon the opposite side of the pivot 34^a to limit the rocking movement of the rocker 33^a.

In this modification the rocker 33^a is similar to that heretofore set forth in connection with

Figures 1 to 4, inclusive, except that the ball member 36^a is enclosed within a glass tube 63^a which is mounted between the end plates 37^a and is sealed thereagainst to prevent the entrance of dirt or other foreign matter into the interior of the tube. The utilization of the glass tube in enclosing the ball 36^a therein prevents the fouling of the track provided by the interior of the tube 63^a which would otherwise interfere with the free movement of the ball 36^a.

It will be noted in connection with the modification of Figures 1 to 4, inclusive, that a similar adjustable limit stop is provided at 62 on the opposite side of the pivot 34 from the pin 32.

In the modification of this invention described, it will be apparent that the ball 36^a in its movement over the pivot 34^a provides the force for actuating the lever arm 28 or for actuation of the mercoid switch 60^a. By the utilization of such a ball to provide the actuating force, the motor, whether it be a spring-wound clock or a small synchronous electric motor, which is used for driving the timer need only be of minimum power output as the function provided by such motor is to place the ball in operation, which function may be performed over a relatively long period of time with respect to the precise and instantaneous operation desired and required for the precise timing effected through the actuation of the valve positioned within the low pressure line 8, 9.

Having fully described my invention, it is to be understood that I do not wish to be limited to the details herein set forth, but my invention is of the full scope of the appended claims.

I claim:

1. A timer including a valve member adapted to control the flow of a fluid under pressure, a valve actuating member, a rocker member, means for pivotally supporting the rocker member, means operatively interposed between the valve actuating member and the rocker member for moving the valve actuating member when the rocker member is rocked to one position, the rocker member carrying thereon a weight member adapted to pass over the pivot and to retain the rocker member in position to which it is rocked on its pivot, and a pair of actuating discs having means adjustably positioned upon their periphery for engaging the rocker member to periodically rock the same around the pivot, and means for driving the disc members.

2. In a timer, the combination of a rocker, means for pivotally supporting the rocker between its ends, the rocker providing a trough, a ball mounted in the trough to travel therein over the pivot so that the ball retains the rocker member in the position to which it is rocked on the pivot in accordance with the location of the ball in the trough, a timing means adapted at definite intervals of time to engage the rocker member to rock the same on its pivot, and a means for driving the timing means.

3. In a precision timer having a valve therein adapted to control the flow of fluid in a conduit, the combination of a frame member, means operatively supported by the frame for actuating the valve member, a rocker member for periodically actuating said valve actuating means, means for pivotally supporting the rocker member between its ends, the rocker member providing a

trough having a weighted ball adapted to travel therein, a pair of spaced timing discs, timing elements secured in selected positions around the periphery of said timing discs, said timing discs being spaced apart so that the timing elements carried thereby will engage opposite ends of the rocker member, and means for driving the timing discs so that they will pass through a complete revolution during a definite period of time.

4. In a timer, the combination of a rocker, means for pivotally supporting the rocker between its ends, a rolling member mounted within the rocker to travel therein over the pivot, a rotating timing means having peripheral engaging elements for engaging the rocker member to rock the same on its pivot, means for driving the timing means, actuating means adapted to be engaged by the rocking member and adapted to be actuated by the weight of the rolling member as it is moved over the pivot to rock the rocking member.

5. A timer for actuating a valve member to control the flow of a fluid, means for actuating the valve, a rocker member, means for pivotally supporting the rocker member, means operatively interposed between the valve actuating member and the rocking member for operating the valve actuating member, the rocker member having mounted therein a weighted rolling member adapted to pass over the pivot to cause the rocker member to engage the valve actuating member and to actuate the same under the force of the weighted rolling member, and means for rocking the actuating member on its pivot at definite predetermined time intervals to cause the weighted member to roll over the pivot of the rocking member.

6. In a precision timer for actuating a valve adapted to control the flow of fluid in a conduit, the combination of a frame member, a valve actuating means supported by the frame, a rocker member pivotally supported between its ends by the frame, means carried by the rocker member providing an enclosed track, a weighted rolling member mounted on the track and adapted to travel therealong as the rocker member is rocked on its pivot whereby the weight of the rolling member is utilized to actuate the valve actuating member, and means adapted to engage the rocker member at definite timed intervals to rock the same on its pivot.

7. In a precision timer for operating a valve controlling the flow of fluid in a conduit, the combination of a frame member, means operatively supported by the frame member for actuating the valve, a rocker member for periodically operating said valve actuating member, means for pivotally supporting the valve actuating member between its ends, the rocker member providing an enclosed track, a rolling weighted member adapted to travel in the track, a pair of spaced timing discs, timing elements secured in selected positions around the periphery of said timing discs, said timing discs being spaced apart so that the timing elements being carried thereby will engage opposite ends of the rocker member, and means for carrying the timing discs so that they will pass through a complete revolution during a definite period of time.
